UNITED STATES PATENT OFFICE.

HERMAN A. RABEY, OF CHICAGO, ILLINOIS.

CHAIN ATTACHMENT.

Application filed January 26, 1921. Serial No. 439,945.

To all whom it may concern:

Be it known that I, HERMAN A. RABEY, a citizen of the United States, residing at Chicago, in the county of Cook and State 5 of Illinois, have invented a certain new and useful Improvement in Chain Attachments, of which the following is a specification.

This invention relates to non-skid devices for use with the tires of vehicle wheels. 10 It is illustrated and described herewith in connection with the means of attaching such non-skid devices where they are composed wholly or in part of chain links. It has for one object to provide a means of attachment 15 which can be easily and rapidly put to use without the assistance of any tools whatsoever. Other objects will appear from time to time throughout the specification and claims.

20 The invention is illustrated more or less diagrammatically in the accompanying drawings, wherein—

Figure 1 is a side elevation of the chain in position on a vehicle tire;

25 Fig. 2 is the plan view of the chain showing the attaching link in position at each end of the cross chain;

Fig. 3 is a side elevation of the attaching link;

30 Fig. 4 is an end elevation of the same link from the closed end;

Fig. 5 is a perspective view of the attaching link in position on a chain link;

Fig. 6 shows the attaching link as it has 35 been slipped over a chain link and before it has been rotated to engage the link;

Fig. 7 is the side elevation of the parts in the position of Fig. 6;

40 Fig. 8 shows the parts after the connecting link has been rotated but before it has been drawn down into position;

Fig. 9 is a side elevation of the parts in the same position as Fig. 8;

45 Fig. 10 shows the parts after the attaching link has been drawn down against the chain link;

Fig. 11 is a side elevation of the parts in the position of Fig. 10.

Like parts are designated by like characters throughout.

A is a wire link bent in a roughly U shaped form, having the two oppositely relative ends A' A' which are bent inwardly to form hooks.

50 B is a side chain of the non-skid device. In one end is mounted the link A, and in

the other end is mounted the receiving link B', having the more or less flat side B² adapted to be engaged by the hooks A' A' of the member A.

60 C is a cross chain adapted to be attached at either ends to side chains B B. Mounted at each end of the cross chains are the links A adapted to engage links in the chains B B.

65 The use and operation of this invention are as follows:

For the purposes of the present illustration the invention has been shown in connection with a non-skid device comprising 70 the following elements:

Two side chains made up of chain links adapted to fit the vehicle wheels and lie along its sides opposite to each other. These side chains are connected at appropriate intervals by a number of cross chains secured at their ends to the side chain. The attaching device of the present invention is designed for use in joining the ends of the side chains and in joining the cross chains 75 to the side chains. For both of these purposes it is desirable to have a means of attachment which can be readily used or removed without any tools. It is one of the purposes of the present invention to produce such means.

80 The use of the present invention in the attachment of the cross chains will first be described. The cross chain is subject to the greatest wear and occasionally breaks, and 90 therefore, a new chain must be substituted. This is done as follows:

A piece of link chain of the appropriate length is prepared. In each end of this chain the fastening link is secured. This is 95 done by threading the end of the fastening link through the end of the link chain. The cross chain is now ready for attachment to the side chains. Then one of the hooks of the attaching line is then slipped through the appropriate link in the side chain, and the attaching link is turned so as to cause each of the hooks to overlie a side of the link of the side chain. Thus the cross chain is attached to the side chain.

100 When actually in use the tension on the cross chain is such as to prevent its being turned with relation to the link of the side chain sufficiently to free it therefrom, but when not in use sufficient slack exists to 110 enable the operator to turn the attaching link with relation to the link of the side

chains so as to free it. By this means the cross chain may readily be removed or attached to the side chains, and thus the broken cross chain may be repaired without the use of tools.

The use of this attachment for the side chains is similar to its use above described. The attaching link is threaded into the link at the end of the side chain. It is then slipped over the link at the other end of the side chain, and it is turned so that its two hooked ends overlie that link. The tension on the side chain when the vehicle is in motion is sufficient to prevent the turning of the attaching links with relation to the link which it engages, and so is sufficient to prevent accidental separation of the parts.

Although I have shown an operating invention, still it will be obvious that many changes both of form, shape, and relation of parts may be made without departing materially from the spirit of my invention, and therefore, I wish that my showing be taken as in a sense diagrammatical.

In particular the attaching link of this invention might be used wherever it is necessary or desirable to fasten together a plurality of chain links, thus it might be used in a harness as a belt buckle or as a means for fastening the traces of the harness to a wagon. It might be used in many other forms of connection where some connection is made with a ring, link or loop.

I claim—

1. As a new article of manufacture a non-skid tire chain attachment formed from a plurality of portions of chain, said portions separably joined together by means of a plurality of members each comprising a link shaped in the form of an open loop and

having at its ends oppositely facing hook members permanently spaced apart.

2. As a new article of manufacture a non-skid tire chain attachment formed from a plurality of portions of chain, said portions separably joined together by means of a plurality of members each comprising a link shaped in the form of an open loop and having at its ends oppositely facing hook members, said hook members facing inwardly toward the closed side of said loop and being permanently spaced apart.

3. As a new article of manufacture a non-skid tire chain attachment formed from a plurality of portions of chain, said portions separably joined together by means of a plurality of members each comprising a link shaped in the form of an open loop and having at its ends oppositely facing hook members, each of said hook members lying substantially in a single plane and being permanently spaced apart.

4. As a new article of manufacture a non-skid tire chain attachment formed from a plurality of portions of chains, said portions including a pair of side chains running about the circumference of the wheel and joined by a plurality of cross chains each fastened at each end to one of the side chains and running cross-wise of the tread of the tire or wheel, all of said portions separably joined together by means of a plurality of members, each comprising a link shaped in the form of an open loop and having at its ends oppositely facing hook members, said hook members facing inwardly toward the closed side of said loop.

Signed Chicago county of Cook and State of Illinois, this 24th day of January 1921.

HERMAN A. RABEY.
